CLAIM

The ornamental design for an housing for recording, transmitting or processing information, as shown and described.

DESCRIPTION

FIG. 1 is a front elevational view of an house for recording, transmitting or processing information showing our new design;

FIG. 2 is a rear elevational view thereof;

FIG. 3 is a top plan view thereof;

FIG. 4 is a bottom plan view thereof;

FIG. 5 is a right-side elevation view thereof;

FIG. 6 is left-side elevation view thereof; and,

FIG. 7 is a front, top and left-side perspective view thereof. Broken lines shown in the drawings represent environment only and form no part of the claimed design.

1 Claim, 7 Drawing Sheets
